UNITED STATES PATENT OFFICE.

CARL JOHNSON, OF BOSTON, MASSACHUSETTS.

CAR.

Application filed November 13, 1922. Serial No. 600,531.

To all whom it may concern:

Be it known that I, CARL JOHNSON, a citizen of the United States, residing in Boston, in the county of Suffolk and State 5 of Massachusetts, have invented an Improvement in Cars, of which the following description, in connection with the accompanying drawings, is a specification, like characters on the drawings representing like 10 parts.

This invention relates to cars for carrying coal and the like, which are provided with gates or doors for controlling the discharge of the load.

15 Cars of this character and known to me are provided with mechanism for automatically opening the doors when the loaded cars arrive at the place where the load is to be discharged. The operation of the automatic mechanism is controlled by a trip or device located at the discharging place or station. The doors referred to are closed manually, after the load has been discharged, which is not only costly but objectionable for many reasons.

20 The present invention has for its object to provide mechanism for automatically closing the gates or doors after the load has been discharged.

25 To this end, the automatic door closing mechanism comprises a member or device carried by the car and operatively connected with the door or doors of the car, and a member or mechanism located alongside of 30 the track on which the car travels and cooperating with the member carried by the car, so as to actuate the latter member and close the door or doors thereof after the car is load has been discharged and the car is 35 moving away from the discharging station.

40 In the present instance, the member carried by the car is shown as a pivoted lever, and the member cooperating therewith is 45 shown as an arm or lever pivoted to a carriage which is movable on a stationary framework, preferably located near the discharging station. The lever carried by the car is designed to engage the lever carried by the carriage and move the latter up an 50 inclined runway as the car is moved away from the discharging station. The weight of the carriage is sufficient to cause the lever on the car to be moved so as to close the 55 gates or doors thereof, and at or about the time the gates or doors are closed the lever

on the car passes out of engagement with the lever or arm on the movable carriage and the latter is returned to its starting position, as will be described.

These and other features of this invention 60 will be pointed out in the claims at the end of this specification.

Fig. 1 represents in side elevation a portion of a coal car and a door closing mechanism embodying this invention.

Fig. 2, an end elevation of the car and the door closing mechanism shown in Fig. 1 looking toward the right.

Fig. 3, a detail to illustrate the operation 70 of the invention, and

Fig. 4, a detail in section on the line 4—4, Fig. 1.

Referring to the drawings, *a* represents one form of construction of car for transporting coal or like material. The car *a* 75 will be hereinafter referred to as a coal car and is provided as shown with side doors *b*, *c* located on opposite sides of the car and controlling ports or openings through which the coal is discharged from the car. The doors *b*, *c*, are connected by links 10, 12, with the opposite ends of a lever 13 fast on a rock shaft 14 mounted on the car *a*, and adapted to be turned in one direction to open the doors *b*, *c* and in the opposite direction to close the same.

80 The present invention has for its object to provide mechanism for automatically closing the doors *b*, *c*, after the load has been discharged, and to this end, the car *a* has pivoted to it at 20 a lever 21, which is joined by a flexible connection with one end of the lever 13 fast on the rock shaft 14. The flexible connection may be a cord or chain 85 22 passed about sheaves 23, 24 mounted in brackets 25, 26 attached to the side and end of the car *a*. The chain or cord 22 is connected at one end to a link 27 which is pivotally connected with the lever 13, and said chain or cord is connected to the lever 21 by a turn-buckle 28, by means of which the flexible connection may be adjusted in length to ensure proper closing of the doors *b*, *c*.

90 The lever 21 extends above the car *a* and is adapted to engage the member which cooperates with it and which is located along the track 16 beyond the discharging station.

95 In the present instance, the member which cooperates with the lever 21 carried by the car, is preferably made as a roller 30 loosely 100

mounted on a pin or rod 31 connecting the lower ends of parallel levers or arms 32 which are pivoted at 33 on opposite sides of a carriage, preferably made as herein shown and comprising two side plates or members 34 connected together at their lower ends by a tie rod 35 and at their upper ends by shafts or rods 36, upon the opposite ends of which are mounted wheels 37, which are supported by and movable on an inclined runway 38, which is suitably attached by braces 39 with horizontal top bars 40 of a supporting framework, which latter is fastened to any suitable stationary support 41, see Fig. 1.

The inclined runway 38 is composed as shown of side members, each of which consists of two angle irons separated by a space or slot 42 into which the shafts 36 may extend, as represented in Fig. 1.

The tie rod 35 connecting the side plates of the carriage projects beyond the same and is designed to be engaged by the levers 32 and render them practically a fixed part 25 of the carriage, so that when the lever 21 on the car *a* is engaged with the roller 30, the carriage 34 will be moved up the inclined runway 38. The levers 32 are free to be moved away from the tie rod 35 for a 30 purpose as will be described. The carriage 34 is moved up the inclined runway 38 by the lever 21 after the car has discharged its load and is moving away from the discharging station. At the same time the carriage 35 is being moved up the inclined runway, the lever 21 on the car is being moved backward by the carriage from its dotted line position which it occupies when the doors or gates *b*, *c*, are open into its full line position, see 40 Fig. 1, which it occupies when the doors are closed. At or about the time the doors or gates are closed and the lever 21 is in its full line position shown in Fig. 1, the said lever passes by or out of engagement with 45 the carriage and the latter is then free to travel down the runway to its starting position. It is desirable to control the return movement of the carriage, which is effected by providing a counterweight 50 for the same. The counterweight 50 is carried by one arm 51 of an elbow lever pivotally mounted at 52 on a block 53 attached to the top bar 40 and having its other arm 54 connected by a link 55 with the carriage 34. 55 The arms 51, 54 of the elbow lever are preferably connected by a cross brace 56.

Provision is made for cushioning the return movement of the carriage, and to this end, rubber or other cushioning members 57 are located at the lower ends of the runway and are secured in fixed relation to the runway between clamping members 58, 59, see Fig. 4. The clamping member 58 is screwed upon the threaded end of a rod 60 and engages the cushion 57 and the clamping mem-

ber 59 engages the outside of the runway and is secured on the threaded rod by the nut 61.

In addition, the arm 51 of the counterweight lever is designed to engage a rubber or other cushion 62 supported by the top bar 40 of the framework carrying the runway.

The lever 21 may be guided in its movement by a metal strap or bar 65 attached to the car *a*. Coal cars of the character described are highly useful for transporting coal from a wharf at which a coal barge or vessel is unloading a cargo of coal, to one or more stations or places where the coal is to be discharged, and it may be desirable to permit the empty cars with their doors closed to pass by the discharging stations without engaging the carriage. To this end, the levers 32 are capable of being moved from their operative position shown by full lines in Fig. 1 into an inoperative position indicated by dotted lines in Fig. 1, and said levers are held in this latter position by means of a pin, not shown, but which is inserted by an operator into a hole 70 in the side of the carriage 34.

When the lever 32 is in its inoperative position, the lever 21 on the car can pass freely thereunder.

I claim:

1. The combination with a car provided with a movable door and with means for opening the same, of means for automatically closing said door comprising a device carried by the car and operatively connected with the door opening means, and a device located along the track over which the car travels and cooperating with the device on the car to be engaged thereby and effect movement thereof and close said door and to be moved bodily by the device on the car into a position in which it is rendered inoperative to act on said latter device.

2. The combination with a car provided with a movable door, of a device carried by the car and operatively connected with said door to be moved into one position when said door is opened, and means located along the path of travel of the car and cooperating with the device on the car to be engaged by the latter and be bodily moved thereby while the device on the car is being moved into a second position to effect closing of the door.

3. The combination with a car provided with a door controlling the discharge of the contents of the car, of a device operatively connected with said door to be moved in one direction when the door is opened and to close the door when moved in another direction, and means extraneous to the car and located along the path traveled by the car to be engaged by said device and be bodily moved thereby in one direction to effect movement of the device to close the door.

and movable in the opposite direction independently of said device.

4. The combination with a car provided with a movable door and with means for opening the same, of means for automatically closing the said door comprising a member carried by the car and operatively connected with the door opening mechanism, and a carriage movable on an inclined runway located along the path traveled by the car and in a position to have the carriage moved up on said runway by the member carried by the car.

5. The combination with a car provided with a movable door, of means for automatically closing said door and comprising a member carried by the car and operatively connected with the door, and a cooperating member located along the path traveled by the car and comprising a stationary inclined runway, a carriage movable thereon, a device attached to said carriage and normally projected into the path of movement of the member carried by the car to be engaged by the latter and effect movement of the carriage up the inclined runway and to effect movement of the member carried by the car and close the door.

6. The combination with a car provided with a movable door, of means for automatically closing said door and comprising a member carried by the car and operatively connected with the door, and a cooperating member located along the path traveled by the car and comprising a stationary inclined runway, a carriage movable thereon, a device attached to said carriage and normally projected into the path of movement of the member carried by the car to be

engaged by the latter and effect movement of the carriage up the inclined runway and to effect movement of the member carried by the car and close the door, and a counterweight for said carriage.

7. The combination with a car provided with a movable door, of means for automatically closing said door and comprising a member carried by the car and operatively connected with the door, and a cooperating member located along the path traveled by the car and comprising a stationary inclined runway, a carriage movable thereon, a device attached to said carriage and normally projected into the path of movement of the member carried by the car to be engaged by the latter and effect movement of the carriage up the inclined runway and to effect movement of the member carried by the car and close the door, a counterweight for said carriage, and means for cushioning the movement of the carriage downward on said runway.

8. The combination with a car provided with a movable door, of a lever pivoted to the car and operatively connected with the door, a stationary runway located along the path of travel of the car, a carriage movable on said runway, and a lever pivoted to said carriage and projected into the path of movement of the car to be engaged by the lever on the car and effect movement of the carriage in one direction and movement of the lever on the car in a direction to close the door.

In testimony whereof, I have signed my name to this specification.

CARL JOHNSON.
